UNITED STATES PATENT OFFICE

HENRY H. MORETON, OF SANTA MONICA, CALIFORNIA

OIL CAN

Application filed May 27, 1927, Serial No. 194,775. Renewed January 6, 1930.

This invention is an oil can of the type having means for forcibly ejecting oil from the spout thereof.

One of the objects of the invention is to provide an oil can of the type mentioned constructed of a minimum number of parts, so assembled as to avoid the employment of soldering and welding operations at the joints thereof. A further object is to provide simple means for connecting the spout with the oil forcing apparatus.

The invention will be hereinafter fully set forth and particularly pointed out in the claims.

15 In the accompanying drawing:—

Figure 1 is a longitudinal sectional view illustrating an oil can constructed in accordance with the invention. Figure 2 is an enlarged detail view illustrating the joint between the pump cylinder and the oil can body. Figure 3 is a detail view illustrating the means for connecting the spout with the body of the oil can.

Referring to the drawing, 10 designates the can body which is provided with a contracted neck portion 11 at its top. Projecting into the open lower portion of the body 10 is a false bottom 12 of frusto-conical form, and closing the said lower portion is 30 a can bottom 13. The contiguous peripheral edges of the false bottom 12 and the permanent bottom 13 are joined with the lower edge of the open bottom portion of the body 10 by means of a pressed or rolled joint indicated at 14, the edges being folded or rolled together in a manner well known in the metal working art, to provide a liquid tight permanent joint. When the parts are thus united, a supplemental chamber 15 is provided between the bottom 13 and the false bottom 12, said chamber communicating with the main portion of the can through the medium of perforations 16 in said false bottom 12.

45 The false bottom 12 is provided with an opening surrounded by an inclined flange 17, and extended through the collar provided by the said flange, and supported at its lower end by said collar is a pump cylinder 18, the upper end of which extends through an

opening in the top portion of the can, as illustrated in Figure 1. The edge 19 of the last mentioned opening is rolled or pressed in to engage a complementary portion 20 on the pump cylinder, so as to provide a liquid tight permanent joint between the parts at this location, and also to prevent longitudinal movement of the pump cylinder.

The wall of the pump cylinder at its lower end is contracted to form an annular shoulder and an inlet opening 21 communicating with the chamber 15, and a discharge opening 22 is located above the plane of the false bottom 12. Cooperating with opening 21 is a ball check valve 23, which is normally held to its seat by means of a spring 24, bearing against an abutment 25. Said abutment consists of a disk-like member provided with legs, the ends of which engage the annular shoulder contiguous to the opening 21 so as to retain the abutment in position within the pump cylinder, and perforations being formed therein to permit of ready passage of oil therethrough.

Said abutment member also serves as the abutment for a spring 26, which acts against a piston 27 to normally hold said piston in retracted position. It will be noted, however, that the pressure of the spring 26 is resisted by a second spring 28 encircling the piston rod 29. A portion of said piston rod extends through the top of the cylinder and is provided with a button or enlargement 30, by means of which it may be conveniently depressed. It will be noted that the reaction of the springs 26 and 28 tends to retain the abutment member 25 in its operative position. The cylinder 18 is so positioned that the button 30 will be located directly over the handle 31, which is secured to the can body in any desired manner.

The upper neck portion of the can body is provided with a cup-like member 35, which is mounted in the contiguous portion of the body in suitable manner, but preferably by rolling the two together as clearly shown in Figure 2. The bottom wall of said cup-like member is provided with openings 36 by means of which oil may be introduced into the can body. A feeder tube 37 has its lower

end secured in suitable manner to the pump cylinder 18, so as to receive oil forced out of said cylinder by the piston 27. The other end of said tube extends through the bottom wall of the member 35 and into a tubular valve seat 37, which is located within the lower end of the spout 38. A ball valve 39 is held normally to said seat 37 by a spring 40, reacting against a tapered abutment 41 which is located within the spout. Said spout is mounted within a sleeve-like portion 42 of a closure member 43, which removably engages the cup-like member 35.

If desired, the spout may be provided with a disk 44 slidably engaging the bottom wall of member 35 so that the spout may be rotatable. (See Figure 3). This would permit of the placing of a curved spout in any desired position, should the position of the closure member 43 be varied.

In practice, in assembling the parts, the pump casing 18 is set into the false bottom 12 through the flange 17 and then the false bottom and the main bottom are manipulated into position. The sloping sides of the false bottom allow the pump to be inserted into position so as to extend through the opening in the top of the can body and also so as to permit the feed tube 37 to be inserted through the bottom of the cup member 35. The bottom edge of the can and the two members 12 and 13 are then rolled or pressed together and the edge of the opening through which the upper end of the cylinder extends is connected with the edge 19 by rolling or pressing them together. It is to be understood, of course, that the member 35 has been previously secured in position in the neck of the can by rolling or similar means.

With the parts thus assembled, the closure member 43 with the attached spout 38 may be removed and the can filled with oil through the openings 36 in the bottom of the cup-like member 35, the oil passing through the perforations 17 into the chamber 15. The closure 43 and its attached spout are then placed in position and the can is ready for use. It will be observed that as the piston 27 is depressed and then allowed to rise under the reaction of the spring 26, oil is eventually pumped out of the chamber 15 into the pump cylinder and then ejected through the tube 37 to the spout 38. The valve 23 acts as a check valve on the downward stroke of the piston and the valve 39 also acts as a check valve to be unseated by the force of the downward stroke of the piston.

The advantages of the invention will be readily understood by those skilled in the art to which it belongs. It will be particularly noted that all of the united parts of the can body and the force feeding mechanism are held in non-separable relation by means of rolled or pressed joints, which provide a thoroughly liquid tight union and avoid the

necessity of employing soldering or welding operations. It will also be observed that a very strong oil can may be very quickly produced.

Having thus explained the nature of the invention and described an operative manner of constructing and using the same, although without attempting to set forth all of the forms in which it may be made, or all of the forms of its use, what is claimed is:—

1. An oil can of the character described comprising a can body having an opening in its top, and a supplemental chamber in its bottom portion, a pump mounted within said can body and communicating with said supplemental chamber, operating means for the pump extending through the upper portion of the can body, a cup-like member secured in the top opening of the can and having openings in its bottom wall, a feeder tube connected at one end with the pump casing and the other end extending through the bottom wall of said cup member, a closure engaging said cup member, and a spout carried by said closure, said spout having a portion telescoping with an end of said feeder tube.

2. An oil can of the character described comprising a can body having an opening in its top, and a supplemental chamber in its bottom portion, a pump mounted within said can body and communicating with said supplemental chamber, operating means for the pump extending through the upper portion of the can body, a cup-like member secured in the top opening of the can and having openings in its bottom wall, a feeder tube connected at one end with the pump casing the other end of said feeder tube extending through the bottom wall of said cup member, a closure engaging said cup member, a spout carried by said closure, a tubular valve seat located within said spout and positioned to telescope with an end of said feeder tube, and a spring pressed valve in said spout and normally seated on the end of said valve seat.

3. An oil can of the character described comprising a can body having an opening in its top, a supplemental chamber in its bottom portion, a pump mounted within said can body and communicating with said supplemental chamber, operating means for the pump extending through the upper portion of the can body, a cup-like member secured in the top opening of the can and having openings in its bottom wall, a feeder tube connected at one end with the pump casing and its other end extended through the bottom wall of said cup member, a closure engaging said cup member and having a sleeve-like portion, and a spout telescoping within said sleeve-like portion, said spout also having a portion telescoping with an end of said feeder tube.

4. An oil can of the character described comprising a can body having an opening

in its top, a supplemental chamber in its bottom portion, a pump mounted within said can body and communicating with said supplemental chamber, operating means for the 5 pump extending through the upper portion of the can body, a cup-like member secured in the top opening of the can and having openings in its bottom wall, a feeder tube connected at one end with the pump casing 10 and the other end extending through the bottom wall of said cup member, a closure engaging said cup member and having a sleeve-like portion, a spout rotatably mounted in said sleeve-like portion and provided 15 with an annular disk-like enlargement at its lower end, said spout having means for engaging an end of said feeder tube, and a spring pressed check valve within said spout.

5. In an oil can of the character described 20 comprising a can body provided with a supplemental chamber, a pump casing extending into said chamber and having an inlet opening therein, the wall of said casing contiguous to said opening being contracted to form an 25 annular shoulder, a check valve cooperating with said opening, an abutment located within said pump casing and having legs engaging said shoulder, a spring reacting between said abutment and said valve, a piston within said 30 pump casing, a spring reacting between said piston and said abutment, a spout, and means connecting said pump casing with said spout.

6. An oil can comprising a can body, a can 35 bottom, a perforated false bottom having a portion to space it from the can bottom, the peripheral edges of the can bottom, said false bottom spacing means and the lower edge of said can body being united with each other by a pressed or rolled joint, a pump casing 40 having one end provided with an inlet opening, said end being extended through and supported by said false bottom so as to locate said inlet opening within the space between said false bottom and said can bottom, 45 the other end of said casing being projected through and secured to the upper portion of said can body, a spout carried by the can body, a feed tube connecting the pump casing with said spout, a piston mounted to work within the pump casing, and operating means 50 for said piston.

7. An oil can comprising a can body, the 55 upper portion of which is provided with an opening, a can bottom, a perforated false bottom having a portion to space it from the can bottom, the peripheral edges of the can bottom, said false bottom spacing means and the lower edge of said can body being united with each other by a pressed or rolled joint, 60 a pump casing having a circumferential enlargement, the edges of the opening in the upper portion of the can body being shaped to conform to said enlargement on the pump casing so as to support the pump casing with 65 its inlet opening within the space between

said false bottom and said can bottom, a spout carried by the can body, a feed tube connecting the pump casing with said spout, a piston mounted to work within the pump casing, and operating means for said piston.

8. An oil can comprising a can body, a can 70 bottom, a perforated false bottom having a portion to space it from the can bottom, the peripheral edges of the can bottom, said false bottom spacing means and the lower edge of said can body being united with each other by a pressed or rolled joint, a pump casing having one end provided with an inlet opening, the other end of said casing being projected through an opening in the upper portion of said can body, the edge of said opening having a rolled interlocking engagement with a complementary interlocking portion on the pump casing so as to prevent longitudinal movement of said pump casing, a spout carried by the can body, a feed tube connecting the pump casing with said spout, a piston mounted to work within the pump casing, and operating means for said piston.

In testimony whereof I have hereunto set 90 my hand.

HENRY H. MORETON.
